(57) **CLAIM**

We claim the ornamental design for a portable basketball system, as shown and described.

DESCRIPTION

FIG. 1 is a perspective view of a first embodiment of a portable basketball system showing the new design, as viewed from the front, left, and top.

FIG. 2 is a perspective view thereof, as viewed from the rear, right, and top.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a perspective exploded view thereof, as viewed from the front, right, and top.

FIG. 10 is a perspective exploded view thereof, as viewed from the front, left, and top.

FIG. 11 is a perspective exploded view thereof, as viewed from the rear, left, and top.

FIG. 12 is a perspective exploded view thereof, as viewed from the rear, left, and bottom.

FIG. 13 is a perspective exploded view thereof, as viewed from the rear, right, and bottom.

FIG. 14 is a perspective exploded view thereof, as viewed from the rear, right, and top.

FIG. 15 is a perspective view of an alternative embodiment of a portable basketball system showing the new design, as viewed from the front, left, and top.

FIG. 16 is a perspective view thereof, as viewed from the rear, right, and top.

FIG. 17 is a front view thereof.

FIG. 18 is a rear view thereof.

FIG. 19 is a left side view thereof.

FIG. 20 is a right side view thereof.

FIG. 21 is a top view thereof.

FIG. 22 is a bottom view thereof.

(Continued)

FIG. 23 is a perspective exploded view thereof, as viewed from the front, right, and top.

FIG. 24 is a perspective exploded view thereof, as viewed from the front, left, and top.

FIG. 25 is a perspective exploded view thereof, as viewed from the rear, left, and top.

FIG. 26 is a perspective exploded view thereof, as viewed from the rear, left, and bottom.

FIG. 27 is a perspective exploded view thereof, as viewed from the rear, right, and bottom; and,

FIG. 28 is a perspective exploded view thereof, as viewed from the rear, right, and top.

In the drawings, the broken lines shown in the figures depict unclaimed subject matter and form no part of the claimed design.
